UNITED STATES PATENT OFFICE

2,542,166

PRODUCTION OF ARTIFICIAL MATERIALS

William Ivan Taylor, Spondon, near Derby, England, assignor to Celanese Corporation of America, a corporation of Delaware

Application June 21, 1946, Serial No. 678,501
In Great Britain June 29, 1945

5 Claims. (Cl. 242—157)

1

This invention relates to the production of artificial materials and particularly to the production of artificial filaments and filamentary yarns by the spinning or extrusion of a spinning solution into a zone containing a setting medium, e. g. an evaporative atmosphere.

In the spinning of artificial filaments in this manner stationary guides are commonly employed for conducting the freshly spun filaments in the form of a yarn, or bundle of filaments, through the path that they follow after emerging from the setting zone. It has been found that the continual running of the filaments in contact with a stationary guide wears a nick in the surface of the guide, even when the guide is made of specially hardened material to resist wear. When this occurs the filaments are apt to be individually broken as they pass in contact with the guide, and to become entangled with one another and with the apparatus employed in their production and treatment. The difficulty seems to be the greater, the softer the outer surface of the filaments. It is an object of the present invention to provide a guide and a method of using it in which this disadvantage is overcome or substantially reduced.

According to the present invention, in the spinning of artificial filaments the freshly spun filaments are guided by contact with a guide surface and the guide surface is moved slowly to and fro across the line of travel of the filaments, the form of the guide surface and its rate of movement being such that a path of the filaments is substantially unaffected by the movement. By this procedure the drag of the filaments against the guide surface is distributed over a substantial area of that surface instead of being concentrated on a narrow part thereof and the tendency for nicks to be cut in the guide surface is substantially overcome.

In order that the movement of the guide shall not substantially affect the path travelled by the filaments it is desirable that the form of that part of the guide surface with which, at any moment, the yarn is in contact, and its orientation with reference to the line of travel of the filaments towards and from it should be substantially the same irrespective of the guide movement. The simplest way to achieve this is to make the operative part of the guide in the form of a straight edge and to give the guide a rectangular motion substantially parallel to the line of the edge. Thus the guide may conveniently be cut out of flat sheet metal, the operative edge being suitably rounded and smoothed.

2

Since the tendency for nicks to be formed in the guide surface is substantially overcome, it is not essential that the guide should be made of specially hardened material; any wear that does take place is uniformly distributed along the edge and does not give rise to filament breakages.

The invention may be usefully applied to any spinning process in which freshly spun artificial filaments are passed in sliding contact with a guide surface. Where, as is commonly the case, a large number of continuous filament yarns are produced on a single machine having a long series of guides, one for each yarn, the several guides serving the same purpose in respect of the several yarns produced may be mounted on a common member and moved to and fro by a common mechanism acting on that member. Thus where the continuous filament yarns, emerging 10 from the spinning zone, pass round a feed roller by which they are drawn out of the spinning zone and forwarded to a twisting and winding device or other yarn collecting device, back guides may be employed behind the feed roller 15 by which the yarns having passed part way round the feed roller are led away from the surface thereof and allowed to return thereto, and these guides may be mounted on a common traverse bar extending the length of the machine and reciprocated by a cam at the end of the machine. Similarly, any other series of guides provided for the guiding of the several yarns 20 may be similarly disposed and may, in fact, be operated by the same cam that operates the feed roller back guides.

When each yarn passes round a plurality of guides on its way to the feed roller by which it is drawn from the point of extrusion, it is of greater importance that the later guide or guides 30 should be of the kind here described than the earlier, since the tension in the yarn, and therefore the friction and wear exerted by it, increase from guide to guide.

By way of example, one form of yarn guide 45 arrangement in accordance with the present invention, will now be described in greater detail with reference to the accompanying drawings in which:

Fig. 1 is a sectional side elevation of the yarn guiding arrangements.

Fig. 2 is a front elevation, partly broken away, of the mechanism shown in Fig. 1, and

Fig. 3 is a detail of one form of guide used in Figs. 1 and 2.

Referring to Fig. 1 a long series of vertical

spinning cabinets of which the front is indicated at 1 is employed for the production of a series of continuous filament yarns 4, which emerge horizontally from the lower part of the cell 1.

On emerging from the cell 1 at the bottom thereof, the filaments pass under a guide 10, over a lubricating roller 11 and onto a feed roller 12. After passing part way round the feed roller 12 the filaments pass round a back guide 13, over the roller 12 again, and are forwarded to the lappet guide of a twisting and winding device or other form of yarn collecting device (not shown). The guides 10 and 13 are operated by means of a cam 16 in a manner more particularly described hereafter.

The lubricating roller 11 is a long roller extending the whole length of the machine and dipping into a trough 20 of lubricant heated by means of steam pipes 21 lying beneath the trough. The roller 11 is provided with fabric sleeves 22, one for each spinning cell 1, for holding the lubricant and applying it to the filaments 4.

Immediately behind the lubricant trough 20 is a traversing bar 23 extending the whole length of the machine and carried between pairs of flanged rollers 24 mounted on horizontal spindles 25 extending from support brackets 26 secured to the frame of the machine. At each spinning cabinet 1 the traversing bar 23 carries a short, vertical rod 27, slotted at its upper end to receive the yarn guide 10 which, as shown in Figs. 2 and 3, is a sheet metal guide lying in a plane parallel to the front of the machine. The guide 10 is of L-form, the short leg of the L extending downwards and fitting into the slotted part of the vertical rod 27, where it is secured by two small rivets 28. The long leg of the L extends horizontally and its lower edge 29 constitutes the guide surface by means of which the yarn 4 emerging from the spinning cabinet 1 is guided into contact with the lubricating roller 11.

Each yarn proceeds from the lubricating roller 11 over and partly round the feed roller 12. The series of feed rollers 12 serving the series of spinning cabinets 1 are mounted on and driven by a common shaft 30. Behind and parallel to the series of feed rollers 12 is a further traversing bar 31 of rectangular section, this bar being mounted on its edge and being carried by guide rollers 32 rotating in brackets 33, which also serve as lateral guides of the bar 31. At each spinning cabinet the traversing bar carried a horizontal bar 34 similar to the rod 27 and carrying a guide 13 of similar form to the guide 10 described above. In this instance, however, the plane in which the guides lie is horizontal, and, as shown in Fig. 3, the working edge 35 of each guide is not quite parallel to the traversing bar 31 by which it is carried, but is inclined at an angle of about 3° thereto. Each yarn 4, after passing over and partly round the feed roller 12 and round the back guide 13, passes over the feed roller 12 again and on to the twisting and winding device or other collecting device. The slight inclination of the guiding edge 35 to the feed roller shaft 30 maintains a separation between the two parts of the yarn 4 as it first passes over the feed roller at 36 in Fig. 2, and as it passes over for the second time at 37.

The two traversing bars 23 and 31 are connected at one end of the machine by means of a yoke 40 which, between the two bars, carries a cam follower roller 41. The cam follower roller is in engagement with a cam groove 42 cut in the

cylindrical surface of the cam 16, by means of which each of the guides 10 and each of the guides 13 are traversed to and fro once in every seven minutes over a distance of about $\frac{3}{4}$ " along the length of the metier. The length of the guiding edges 29, 35 is about 2". The yarn 4, in its travel from the spinning cabinet 1 to the yarn collecting device, takes up a stable path between the edge of the first traversing guide 10, over the lubricating roller 11 and feed roller 12, round the second traversing guide 13 and over the feed roller again, and this path is not substantially altered by the traversing of the two guides 10, 13. Any wear taking place on the guides is distributed over a distance equal to the length of the traverse, and there is substantially no tendency for nicks to form in the guiding surfaces 29-35. Any slight tendency to extra wear at the ends of the traverse may be overcome by occasionally and slightly shifting the position of the guides along the length of the metier. This may be done, as shown in Fig. 3, by providing in the length of the bar 31 (and the bar 23) a simple turnbuckle 43 with lock-nuts, by which the bars may be adjusted longitudinally. A half turn of the turnbuckle 43 at say, weekly intervals, is sufficient to prevent the development of worn spots at the ends of the working parts of the guide edges 29, 35.

The lubricating roller 11 is driven from the feed roller shaft 30 by means of a chain 44 and sprocket 45 which, by way of a worm (not shown), worm gear 46, worm 47 and worm gear 48, drives a shaft 49. The shaft 49 carries a spur gear (not shown) which drives a gear 50 secured to the lubricating roller 11. The shaft 49 also carries a sprocket (not shown) which, by way of a chain 51 and sprocket 52, drives the cam 16.

Having described my invention, what I desire to secure by Letters Patent is:

1. Method of guiding freshly spun artificial filaments, said method comprising running the filaments in contact with a guide surface that is smooth and continuous over its width, across the line of travel of the filaments, and continually changing the part of said surface with which said filaments contact by moving said guide surface slowly to and fro across said line over a distance at most equal to said width.

2. Method of guiding freshly spun artificial filaments, said method comprising running the filaments over and in contact with a straight edge extending across the line of travel of the filaments, and continually changing the part of said edge with which said filaments contact by moving said straight edge slowly to and fro in a direction parallel to and over a distance at most equal to its length.

3. Apparatus suitable for the guiding of freshly spun artificial filaments, said apparatus comprising a member having a guiding surface that is smooth and continuous over the width thereof, transverse to the line of travel of the filaments over said surface, and means for traversing said member slowly to and fro across said line over a distance at most equal to said width.

4. Apparatus suitable for the guiding of freshly spun artificial filaments, said apparatus comprising a member having a thread-guiding straight edge formed thereon and extending across the line of travel of the filaments, and means for traversing said member slowly to and fro across said line, in a direction substantially parallel to said straight edge and for a distance at most equal to the length of said straight edge.

5. Apparatus suitable for the guiding of freshly spun artificial filaments, said apparatus comprising a member formed of flat sheet metal and having a thread-guiding straight edge that is rounded and smoothed and extends across the line of travel of the filaments, and means for traversing said member slowly to and fro across said line, in a direction substantially parallel to said straight edge and for a distance at most equal to the length of said straight edge.

WILLIAM IVAN TAYLOR.
